LEONARD L. MAXAM, OF SAN PEDRO, CALIFORNIA, ASSIGNOR OF ONE-THIRD TO
CLARENCE S. CREWS, OF SAN PEDRO, CALIFORNIA

PADDED SOUND REPRODUCING HORN

Application filed June 19, 1929. Serial No. 371,995.

This invention relates to sound reproducing instruments.

An object of the invention is the production of a sound reproducer of the type ordinarily termed "loud speakers" which is capable of reproducing sound with extreme fidelity as to tone quality.

Another object is the production of a loud speaker having an extremely natural tone as described, in which the tone fidelity is attained without sacrifice of volume.

A further object is the provision of improvements in that class of loud speakers, which is ordinarily employed in theaters and the like, to reproduce sound accompanying the action depicted cinematographically.

Another object is to provide a very simple means of improving the tone qualities of the conventional sound reproducer, and more particularly of the class of sound reproducers employed for use in conjunction with "sound pictures."

A still further object is the provision of means for improving the tone of a loud speaker, this means being of a very simple nature and may very easily be applied to those sound reproducers already in service, and at a relatively small cost.

A further object is the provision of improvements in sound reproducing horns, which may be employed to correct discrepancies between the tonal characteristics of each of a plurality of horns.

The invention possesses other objects and advantageous features, some of which, with those enumerated, will be set forth in the following description of the invention's particular embodiment which is illustrated in the drawings accompanying and forming a part of the specification.

Referring to the drawings:

Figure 1 is a longitudinal, medial, vertical sectional view of a conventional sound reproducing instrument having the improvement of my invention installed thereupon.

The plane of section is taken upon the line 1—1 of Fig. 2, and the direction of view is indicated by the arrows:

Fig. 2 is a transverse, vertical sectional view taken upon the line 2—2 of Fig. 1, with the direction of view as indicated by the arrows.

In terms of broad inclusion, the improvement in sound reproducers, which constitutes the present invention comprises a padding or covering of sound dampening material for all or portions of the area of the amplifying element of the reproducer which is otherwise exposed to the sound vibration emanating from the reproducing unit of the instrument, as well as from outside sources. As indicated in the objects enumerated above, the improvement of the present invention is particularly applicable to that type of loud speaker which is employed for the reproduction of the sound accompanying the cinematograph depiction of action. In the construction of this type of sound reproducing instrument, considerable effort has been expended toward the accurate reproduction of sound throughout the entire audio range. Particular emphasis has been laid upon the reproduction of sound of the lower register. To such an extent has this effort been carried, that in the case of many of the loud speakers now in use, the notes of the lower register are overemphasized, resulting in a distortion of the ultimate sound characterized by unnatural rumbling. Particularly true is this when it is necessary to provide for relatively great amplification of sound—as for example, in the case of sound pictures.

Loud speakers employed for this service, are frequently assembled into a bank of four or more, each a complete reproducing instrument; but all of them receiving the same electrical energy and from the same translating apparatus whereby this electrical energy is derived from light energy or

some other source. Such a bank of speakers is arranged closely behind the projection screen, the speakers being so distributed that the sound emanating therefrom is not centralized, i. e., the sound appears to the audience upon the opposite side of the screen, to emanate from the entire area of the screen. The present invention contemplates the provision of a covering of sound vibration dampening material, not only for each of the individual sound reproducing instruments of which the bank of speakers is composed, but also an enclosing partition completely encasing all of the speakers with the exception that a suitable aperture or apertures are provided in register with the amplifying elements of the speakers through which the sound may pass unrestrictedly.

20 Describing the invention in one of its several possible embodiments, the figures of the drawings disclose a sound reproducer composed of a pair of loud speakers 5 and 6. Each speaker is composed of an electrical unit 7 and 8 respectively, whereby electrical energy is translated to sound vibrations and, an amplifying unit in the form of tortuous horns 9 and 11 respectively. Each horn includes a mouth or bell end 12 in communication through the throat portion 13, with the smaller end 14 to which the unit 7 or 8, as the case may be, is connected. Each horn is so designed that its air column 16 gradually increases in cross sectional area from the small end 14 of the horn, to the bell end 12.

The speakers 5 and 6 are suitably supported upon a framework indicated in its entirety at 17, and are so arranged that the sound emanates from the speakers in convergent lines, i. e., the upper speaker is directed slightly downwards, while the lower speaker is directed angularly upwards as clearly shown upon Fig. 1. The frame 17 ordinarily consists of vertical corner posts 18, and longitudinally and transversely extending horizontal braces 19 and 20 respectively. These members may be composed of any suitable stock such as angle iron suitably riveted or otherwise securely fastened together in proper assembled relationship.

Heretofore, the frame 17 of such a bank of speakers, was left open. My invention contemplates the provision of suitable front, back, side, top, and bottom partitions 21, 22, 23, 24, and 26 respectively. These partitions are composed of any suitable sound vibration dampening material such as felt, sheets of cotton batting or the like; and are so arranged that they completely encase the several speakers 5 and 6, with the exception that the front partition 21 is provided with an aperture 27 in register

with the bell ends 12 of both horns 9 and 11.

Furthermore, each of the horns 9 and 11, is provided with coverings or linings 28 preferably of the same material as that of which the partitions are composed. These coverings are secured to the horns 9 and 11 in such position that they completely cover all surfaces of the horns preferably both inside and out, adjacent the bell end thereof, and extend downwards into the throat thereof as clearly shown upon Fig. 1. The coverings may be attached to the horns in any suitable manner such as by the use of any suitable adhesive, and extend down into the throats of the horns as far as convenient, taking into consideration the tortuous nature of the throats. Furthermore, a sheet 29 of similar sound dampening material extends between the extreme ends of the bells 12 of both horns 9 and 11.

It has been found in actual operation that when a bank of speakers similar to that described above, is employed without the padding or partitions of sound dampening material, the horns 9 and 11 themselves, are set into vibration in resonance with the vibration of the air columns. The production of unnatural tones such as the low rumbling so frequently present in the sound produced by amplifying devices of this general character, is largely attributable to this phenomenon, inasmuch as the vibration of the material of which the horns themselves are composed, interferes with the normal vibration of the air column. This accounts for the improvement in the tone accomplished by providing the linings and partitions above described, inasmuch as they dampen the vibrations as they approach the horns and thus largely prevent the horns being set into vibration, thereby enabling the sound vibrations of the air column itself, to issue from the bell of the horn undistorted and without the development of any sound interference.

A bank of speakers such as that above described, is conventionally employed by being positioned closely behind the projection screen. Consequently, each bank is preferably mounted upon suitable castors 31 or their equivalent. This positioning of the bank results in the development of a reflection of sound waves, inasmuch as the vibrations issuing from the bells of the horns, are found to impinge against the back of the screen and rebound partially at least, back into the horns themselves. In this manner, additional sound interference has been developed through the reverberation of the sound reflecting from the after side of the screen, intermingling with the sound issuing directly from the horns. The linings 28 upon the interior surfaces of the horns, is found to eliminate this undesirable condi-

tion to a very great extent; and the sheet 29 extending between the bells of the horns, also catches and dampens a large amount of these reflected sound waves. Furthermore, 5 the partitions 21, 22, 23, 24, and 26, intercept the remaining portion of these reflected sound waves, as well as sound waves emanating from other sources, which are apt to impinge upon the otherwise unprotected horns to develop unpleasant and undesirable vibrations thereof.

It has been found that the provision of the linings and partitions as above described, upon a conventional bank of loud speakers, 15 results in the production of sound having remarkable fidelity of tone even though amplified to a very great extend. While the notes of the lower register, as well as the higher notes, are reproduced with a high 20 degree of perfection, the rumbling as well as other distortion so frequently developed in speakers of this general class, is largely, if not completely eliminated; with the result that any sound reproduced by such a 25 bank of speakers whether instrumental music or the voice, in either speaking or singing, is reproduced with a high degree of accuracy.

I have found that the improvements constituting the present invention, are also of extreme value in connection with the banks or "towers" of sound reproducing instruments which are conventionally employed to reproduce the sounds accompanying cinematographically depicted action, inasmuch as they permit of accurate adjustment of the padding upon each of the several horns of a tower, so as to cause each reproducing horn to have exactly the same tonal characteristics as the other horns of the same bank. 30 In manufacturing these loud speakers, every effort is expended to cause the several speakers of a bank to have exactly the same tonal characteristics; but owing to the exigencies of manufacture, such as variation in the quality of the wood employed in the construction of the horns, and other variations in quality of material and the like, detection of which is impossible, it is practically beyond possibility to so construct the horns that they all have exactly the same tone. However, by varying the quantity and positioning of the padding when adapting the improvements of the present invention to the several speakers of a bank, these inherent discrepancies of tonal characteristics may be very nearly, if not completely eliminated; with the result that the sound emanating from each of the several speakers of the bank, blends perfectly with that from the other speakers, at least with such a degree of nicety that any variation between their respective sound outputs, can not be detected by the ear.

It is to be understood that the details of

the invention as herein disclosed, are subject to alteration within the spirit or scope of the appended claims.

I claim:

1. A loud speaker comprising a frame, a sound reproducer mounted thereon and including a sound amplifier, and a covering of vibration dampening material carried by said frame and completely enclosing said reproducer with the exception of an opening 75 therein in register with said amplifier.

2. A loud speaker comprising a frame, a sound reproducer mounted therein and including an amplifying horn, a covering of vibration dampening material carried by the frame, said covering encasing said reproducer and having an aperture therein in register with the bell end of said horn, and a sheet of vibration dampening padding material covering the surfaces of said horn adjacent the bell end thereof and otherwise exposed to sound vibration.

3. A loud speaker comprising a frame, a plurality of sound reproducers mounted thereon, each including an amplifying horn, a covering of vibration dampening material carried by said frame, said covering completely encasing said reproducers with the exception of an aperture therein in register with the bell ends of said horns, and sheets of vibration dampening material covering surfaces of said horns adjacent the bell ends thereof otherwise exposed to sound vibration.

4. A loud speaker comprising a frame, a plurality of sound reproducers mounted thereon, each including an amplifying horn, a covering of vibration dampening material carried by said frame, said covering completely encasing said reproducers with the exception of an aperture therein in register with the bell ends of said horns, sheets of vibration dampening material covering surfaces of said horns adjacent the bell ends thereof otherwise exposed to sound vibration, and a sheet of vibration dampening material extending between said horns adjacent the bell ends thereof.

5. In a loud speaker, a sound reproducer comprising an amplifying horn, and a vibration dampening housing therefor comprising a framework and sheets of padding material stretched upon said framework about said reproducer, said padding material engaging the edges of said horn to completely close the space defined by said framework.

6. In a loud speaker, a sound reproducer comprising an amplifying horn, and a vibration dampening housing therefor comprising a framework, sheets of padding material stretched upon said framework about said reproducer, said padding material engaging the edges of said horn to completely close the space defined by said framework, and padding secured to the inside of said horn 125

and extending from the outer edges thereof back into the throat thereof.

7. In a loud speaker, a sound reproducer comprising an amplifying horn, and a vibration dampening housing therefor comprising a framework, sheets of padding material stretched upon said framework about said reproducer, said padding material engaging the edges of said horn to completely close the space defined by said framework, padding secured to the inside of said horn and extending from the outer edges thereof back into the throat thereof, and padding secured to the exterior surface of said horn throughout substantially the entire area thereof.
- 15 In testimony whereof I have signed my name to this specification.

LEONARD L. MAXAM.
